UNITED STATES PATENT OFFICE.

HAL R. STAFFORD, OF PLAINFIELD, NEW JERSEY.

INTERCEPTING-VALVE FOR COMPOUND ENGINES.

1,175,087.

Specification of Letters Patent.

Patented Mar. 14, 1916.

Application filed October 2, 1915. Serial No. 53,693.

To all whom it may concern:

Be it known that I, HAL R. STAFFORD, of Plainfield, in the county of Union and State of New Jersey, have invented a certain new and useful Improvement in Intercepting-Valves for Compound Engines, of which improvement the following is a specification.

My present invention is an improvement upon that for which Letters Patent of the United States No. 1,066,232 were granted to me under date of July 1, 1913, and issued to me under date of July 1, 1913, and its object is to enable the advantages thereof to be attained with a simplification of mechanism and corresponding economization of structural and maintenance cost.

The improvement claimed is hereinafter fully set forth.

In the accompanying drawings: Figure 1 is a longitudinal central section through an intercepting valve mechanism embodying my invention, the parts being shown in position when working as a compound engine, and; Fig. 2, a similar section, the parts being shown in position when working as a simple or single expansion engine.

Referring to the drawings, the intercepting valve mechanism is, as in Letters Patent No. 1,066,232 aforesaid, fitted in a casing, 16, of substantially cylindrical form, which is separate from the high pressure cylinders of the engine, and adapted to be connected detachably thereto and supported in any suitable and convenient manner. The interior of the casing is divided, by transverse partitions, 16^b, 16^c, and 16^d, into a high pressure exhaust chamber, 17; an independent or direct exhaust chamber, 18; a receiver chamber, 19; and a live steam chamber, 20. Two curved passages, 17^a, lead from the high pressure exhaust chamber, 17, to openings in the wall of the casing, 16, which, when the casing is secured in position on the high pressure cylinders, register with the openings of the exhaust passages of said cylinders, 40 ball joint rings being interposed at the joints to insure tightness while permitting a limited degree of relative movement. Instead of controlling communication between the high pressure exhaust chamber and the receiver by an intercepting valve, and between the high pressure exhaust chamber and the direct exhaust chamber by a separate and independent direct or emergency exhaust valve, as has ordinarily been the practice prior to the invention of Patent No. 1,066-, 55 aforesaid, I provide, as in said patent, a

single valve, 21, which, operating in combination with a reducing valve, performs the functions of the two independent valves of the prior art, and which I therefore term an intercepting and direct exhaust valve. The valve, 21, is fixed upon a stem, 22, by the movements of which, as presently to be described, it is either closed on a seat, 16^e, surrounding an opening in the partition, 16^b, when the locomotive is working as a compound engine, as shown in Fig. 1, or on a seat surrounding an opening in the partition, 16^c, when the locomotive is working as a simple engine, as shown in Fig. 2. The seat, 16^e, is made integral, and in line axially, with the operating cylinder, 24, hereinafter specified, and is connected therewith by radial ribs or webs, 24^b.

The stem, 22, of the intercepting and direct exhaust valve carries, upon one of its ends, a properly packed piston, 23, which is fitted to move longitudinally in a combined operating and dash pot cylinder, 24, connected detachably to one of the ends of the casing, 16, in which there is formed an opening through which said cylinder, together with the valve, 21, and its stem, may be inserted and removed, as desired. The stem, 22, passes, with a comparatively loose fit, through an opening in the inner head of the cylinder, and the outer end of the cylinder is closed by a detachable head, 24^a, in which is formed an opening, communicating, by a pipe, 25, with the casing of a manually operated simpling or operating valve, located in the cab of the locomotive and controlling the supply of steam from the boiler to the cylinder through the pipe, 25. The simpling valve mechanism is fully described and shown in Patent No. 1,066,232, and as it does not, in and of itself, form part of my present invention, it is not herein described.

The stem, 22, is reduced in diameter for a portion of its length, on the side of the valve, 21, farther from the cylinder, 24, and a reducing valve dash pot piston, 27, is formed or fixed upon it, at the end of its reduced portion, said piston fitting, and working longitudinally, in a reducing valve dash pot, 28^a, formed in a tubular reducing valve, 28, said valve having a piston, 28^b, adjoining its end in which the dash pot is formed, a piston, 28^c, of smaller diameter, at its opposite end, and an intermediate piston, 28^d.

The mechanism, so far as hereinbefore de-

scribed, accords, except as to the reducing valve, with that of Letters Patent No. 1,066,232, aforesaid, and the further improvement of my present invention will now be described. The reducing valve pistons, instead of working in a main steam admission valve, as in said patent, are, in my improved construction, fitted directly in a sleeve or bushing, 30, which is fixed in the 5 partition, 16^a, of the casing, and in a cylinder, 31, projecting therefrom and closed, at its outer end, by a removable head, 31^a, said bushing extending through the live steam chamber, 20, and the receiver chamber, 19. 10 Live steam from the chamber, 20, is continuously admitted to the interior of the bushing, 30, through ports, 30^a, therein. The main live steam admission valve, 29, of Patent No. 1,066,232, is, under my present invention dispensed with, and its function, *i. e.*, that of cutting off the flow of live steam to the receiver chamber when working compound, is performed by the intermediate piston, 28^d, of the reducing valve, which, by 15 passing over ports, 30^c, leading through the bushing, 30, into the receiver chamber, 19, prevents the egress of steam from the interior of the bushing to the receiver chamber and communicating high pressure cylinders. 20 The other function of the main live steam admission valve, *i. e.*, to move the intercepting and direct exhaust valve, 21, into compound position when the pressure is released from the piston, 23, is also performed 25 by the reducing valve, which, by reason of the difference in the diameters of its pistons, 28^b and 28^c, is constantly subject to a preponderance of pressure acting toward the 30 larger piston, 28^b. 35 40 It will be seen that by the modification of structure of the reducing valve above described, it is enabled to perform two functions additional to its original one, and the main live steam admission valve is thereby dispensed with, correspondingly effecting a 45 substantial simplification of the mechanism and a reduction of the cost of manufacture, and rendering the entire appliance more positive in its action and more easily maintained in operative condition.

The smaller piston, 28^c, of the reducing valve, is constantly subject to atmospheric pressure on its outer side, through the chamber of the cylinder, 31, which is closed by 55 the head, 31^a, and through a pipe, 31^b, leading therefrom to a separate exhaust pipe, 32, which discharges into the smoke box of the locomotive.

In operation, when it is desired to work 60 the locomotive as a simple engine, steam from the boiler is admitted by the engineer to the operating and dash pot cylinder, 24, by the manipulation of the operating or simpling valve mechanism. The intercepting and direct exhaust valve, 21, is thereby

moved by the pressure on the outer side of the piston, 23, to its seat in the partition, 16^c, closing communication between the high pressure exhaust chamber and the receiver chamber, and opening communication between the high pressure exhaust chamber and the direct exhaust chamber and separate exhaust pipe. The valve is seated without shock by reason of the compression of the fluid contents of the dash pot formed by the space on the inner side of the piston, 23. In this traverse, the reducing valve, 28, is moved by the pressure of the piston, 27, on the bottom of the dash pot, 28^a, into position in which the piston, 28^d, opens the ports, 30^c, thereby allowing boiler steam, at a reduced pressure (determined by the relative diameters of the pistons, 28^b and 28^c) to flow from the live steam chamber, 20, through the space in the bushing, 30, surrounding the reducing valve, and the ports, 30^c, into the receiver chamber, 19, and thence directly to the lower pressure cylinders. The exhaust from the high pressure cylinders is discharged directly through the separate exhaust pipe, 32.

When it is desired to work as a compound engine, the engineer releases the pressure from the operating cylinder, 24, by proper movement of the simpling valve mechanism, whereupon the pressure of the live steam on the differential pistons, 28^b and 28^c, of the reducing valve, moves the valve, 21, to its seat in the partition, 16^b, and brings the reducing valve into the position shown in Fig. 1. The exhaust steam from the high pressure cylinders is then discharged into the receiver chamber, and thence to the low pressure cylinders, and the direct supply of live steam to the low pressure cylinders is cut off.

Among the advantages which my present invention attains, in addition to those of the construction set forth in Patent No. 1,066,232 aforesaid, there are specially to be noted those of a material reduction in the number of packing rings as compared with prior intercepting valve mechanisms, and the performance of a number of functions by a single unit, thereby effecting a material reduction in the number of working parts.

I claim as my invention and desire to secure by Letters Patent:—

1. In a compound engine, the combination of an intercepting valve casing having a separate exhaust chamber, a receiver chamber, and an interposed high pressure exhaust chamber, openings being formed in the partitions between said chambers; an operating cylinder fixed to the casing; a piston working therein; a stem fixed to said piston; a single valve fixed to said stem and adapted to control each of the partition openings; a reducing valve movable by and in line with said stem, and having a limited

- degree of traverse independent thereof; a fixed bushing in which said reducing valve is fitted to operate and which communicates with a source of live steam supply; ports 5 leading from the interior of the bushing to the receiver chamber; an end piston head, 28^b, carried by the reducing valve and controlling communication between the interior of the bushing thereof and the receiver 10 chamber, when the engine is working simple; an opposite end piston head, 28^c of smaller diameter closing communication between the interior of the bushing and the atmosphere; and an intermediate piston head, 28^d, 15 also carried by said valve and cutting off steam admission through the ports, 30^e, leading from the interior of the bushing to the receiver chamber, when the engine is working compound.
- 20 2. In a compound engine, the combination of an intercepting valve casing having a separate exhaust chamber, a receiver chamber, and an interposed high pressure exhaust chamber, openings being formed in the partitions between said chambers; an operating cylinder fixed to the casing; a piston working therein; a stem fixed to said piston; a single valve fixed to said stem and adapted to control each of the partition openings; a 25 reducing valve movable in line with said stem; a fixed bushing having bores of different diameters in which said reducing valve is fitted to operate and which communicates with a source of live steam supply; ports leading from the larger bore of 30 the bushing to the receiver chamber; end
- pistons on the reducing valve fitting the differential bores of the bushing; and an intermediate piston on said valve which cuts off steam admission through the receiver 40 ports of the bushing.
3. In a compound engine, the combination of an intercepting valve casing having a separate exhaust chamber, a receiver chamber, an interposed high pressure exhaust 45 chamber, and a live steam supply connection, openings being formed in the partitions between the chambers; an operating cylinder fixed in the casing; a piston working therein; a stem fixed to said piston; a 50 single valve fixed to said stem and adapted to control the partition openings; and a differential piston valve member which is controlled by said stem, and which is provided with an intermediate piston which 55 cuts off the admission of steam at reduced pressure from the live steam supply connection to the receiver chamber.
4. In a compound engine, the combination of an intercepting valve casing, an intercepting valve controlling steam passages 60 therein, and a reducing valve operating in connection with said intercepting valve and comprising a tubular body, two end pistons 65 of differential diameters, and a perforated intermediate piston corresponding in diameter with the larger end piston.
